UNITED STATES PATENT OFFICE.

JOHN BERG, OF CHICAGO, ILLINOIS, ASSIGNOR TO METAL SPECIALTIES MANUFACTURING COMPANY, OF CHICAGO, ILLINOIS, A CORPORATION OF ILLINOIS.

ELECTRIC CONNECTER.

Application filed August 31, 1921. Serial No. 497,099.

This invention relates particularly to electric connectors, such as are used for connecting electric conductors to any electrical device, such as an electric lamp.

5 The primary object is to provide a connector with an improved switch device whereby the circuit may be established or broken with facility, as desired.

The invention may be employed very advantageously in connection with either a dash-lamp or an exploring lamp for automobiles.

The invention is illustrated in its preferred embodiment in the accompanying 15 drawing, in which—

Fig. 1 represents a plan view of a dash-lamp constructed in accordance with the invention, the actuating stem of the switch being shown in section and the handle 20 thereof being shown in dotted lines; Fig. 2, a section of the device taken parallel with the plane of the paper, the inner parts being shown in elevation; and Fig. 3, an enlarged sectional view taken as indicated at line 3 25 of Fig. 1.

The device, in the embodiment shown, comprises a metal sleeve or shell A equipped at one end with an attaching flange A' and at the opposite end with a hood or annular 30 supporting member A²; a reflector or shield A³ removably mounted on the member A²; a rotatable and longitudinally movable plug B mounted in the sleeve A and itself comprising a metal sleeve 1 and an insulating plug 1^a snugly fitted in the sleeve 1; a spring contact B' centrally mounted in the plug B and having connected with its base end an electric conductor B²; and an incandescent lamp or bulb C having a shank 2 equipped 35 with lateral studs 3 which engage bayonet slots 4 with which the sleeve A is provided at its outer or front end, the shank of the lamp being provided with a central contact 5 which is adapted to make contact with the central contact B' of the plug.

The shell A is provided with a cam-slot 6 which is provided at its upper end with an offset or bay 6^a. An operating handle 7 is provided which has a reduced shank 7^a 40 extending through the cam-slot 6 and whose inner end is threaded and secured in a threaded lateral socket with which the plug B is provided.

A coil spring 8 is interposed between the 45 inner end of the shank of the lamp and the

adjacent end of the plug. This coil spring has one end bearing against the end of the lamp-shank and has the other end projecting into an annular recess 9 which is formed by reducing the end portion of the insulation 60 plug 1^a. An annular groove 9^a is provided at or near the base of the reduced portion of the insulation plug, and the extremity of the spring is turned inwardly and entered in said annular groove, as indicated at 9^b, so 65 that the spring is anchored to the insulation plug. This is a matter of convenience in assembling and also serves to prevent loss of the spring when the lamp-bulb is removed or the parts are disassembled. 70

The spring contact B' comprises a small metal tube 10 in which is mounted a spring plunger 10^a and a spring 10^b which is confined between the plunger and a small metal plug 10^c at the opposite end of the tube 10. 75 The conductor B² is secured to the contact B' by means of a screw 11.

In the illustration given, the lamp C has its shank provided with a metal shell which makes contact with the metal sleeve A; and 80 when the metal sleeve A is applied to the metal dash of an automobile one terminal of the lamp is thus grounded, while the central terminal of the lamp makes contact with the spring contact B' of the connector, assuming the plug B to be in the elevated or forward position illustrated. 85

The contact is established by rotating the plug thru the medium of the handle 7 and moving the stem thru the inclined cam-slot 90 6. In this operation, the spring 8 is placed under greater compression, and at the end of the movement the shank 7^a snaps into the offset or recess 6^a of the slot, so that the plug will be locked in the forward position. 95 In this position, the plunger 10^a of the spring contact B' is forced rearwardly against the resistance of the spring 10^b, thus insuring good contact. When the handle 7 is moved to withdraw the shank 7^a of the 100 operating handle from the recess 6^a, the spring 8 will then operate to force the plug B back or rearwardly, thus withdrawing the plunger-form contact 10^a from the central contact of the lamp. 105

The improved device is simple in construction, capable of being cheaply manufactured, and is easily operated.

The foregoing detailed description has 110 been given for clearness of understanding

only, and no unnecessary limitations should be understood therefrom, but the appended claim should be construed as broadly as permissible in view of the prior art.

What I regard as new, and desire to secure by Letters Patent, is—

A device of the character set forth, comprising a shell equipped at one end with an attaching flange adapted to be secured to a dash and equipped at the other end with bayonet slots, said shell being provided intermediately with a cam-slot having an off-

set or recess at its forward end, a slidable plug in said shell equipped with a laterally projecting handle whose stem is movable in said slot, a spring contact mounted in said plug and adapted to make contact with the terminal of a lamp or plug entered in the free end of said shell, and a spring secured to the end portion of said first-named plug and adapted to retract the plug and break the circuit. 15 20
